STABILIZATION OF GLYCERIDE OILS

Sidney Musher, New York, N. Y., assignor to
 Musher Foundation Incorporated, New York,
 N. Y., a corporation of New York

Application October 9, 1939, Serial No. 298,642

6 Claims. (Cl. 99—163)

This invention relates to the stabilization of glyceride oils and particularly to the stabilization of oils released from an emulsified or dispersed phase as in the separation of oil from the dispersed phase of an oil-in-water dispersion.

It has not been found readily possible to add antioxidants or stabilizers directly to many types of glyceride oils, particularly when such antioxidants may not be oil soluble or miscible.

It is a primary object of this invention therefore to retard the deterioration of substantially pure oils and particularly of pure glyceride oils and fats by the use of substantially oil insoluble antioxidants or antioxidants that would normally be ineffective or decreased in effectiveness when added to an oil and dissolved therein.

Further, it has been found that many antioxidants have a substantially weakened action when added to pure oils or fats and only give such oils and fats limited additional stability against rancidity and other forms of oxidative deterioration and it is among the further objects of the present invention to provide an improved method of stabilizing oils and fats and particularly glyceride oils and fats in which the antioxidants may be so utilized and combined with such oils and fats as to give them substantially greater stability and cause them to be substantially more resistant to the development of oxidative deterioration and rancidity.

It has also been found that many antioxidant materials when added to or combined with an oil or fat in substantially pure form will leave materials in the oil or fat which, although they initially retard deterioration, nevertheless, after a substantial portion of time or after the oil or fat has stood, will apparently cause a more rapid deterioration or development of rancidity than would result if the pure oil or fat had been permitted to stand or had been stored for the same length of time without any such addition.

It is, therefore, among the further objects of the present invention to provide a method of stabilizing substantially pure oils and fats in such a manner that the antioxygenic effect of the antioxidants may be utilized to the fullest extent without at the same time introducing into the oil or fat agents or materials which will tend to counteract the antioxidants particularly after standing and which may even give rise after a certain period of time to increased deteriorative effects or to substantially greater rancidity than would normally be obtained with the untreated oil or fat.

Still further objects and advantages will ap-

pear from the more detailed description set forth below, it being understood, however, that this more detailed description is given by way of illustration and explanation only, and not by way of limitation, since various changes therein may be made by those skilled in the art without departing from the scope and spirit of the present invention.

In accordance with this invention, I use desirably water soluble stabilizing materials for addition to the aqueous phase of an oil containing aqueous composition and preferably a composition in which the oil occupies the dispersed phase and the water the continuous phase.

The oil or fat and particularly the glyceride oil or fat to which the present invention will be particularly directed, although not limited, may be dispersed or emulsified or otherwise combined with water and aqueous materials to permit of the treatment according to the present application, or in many cases the oil or fat may be used in naturally occurring dispersions of water form.

It has been found that under these conditions many water soluble materials exercise antioxygenic action when placed in the water phase and out of contact with the oil which they do not exercise when placed in the pure fat or oil itself. Among the materials which may give little or greatly decreased antioxygenic effect when added to a pure oil or fat phase, particularly of a glyceride type, and which give a good effect when added to an aqueous phase without direct contact with the oil or fat are the crude sugars, including particularly crude cane and beet sugars.

Under these circumstances the water soluble stabilizing material is in the continuous aqueous phase and is not admixed in the dispersal oil or fat phase.

It is usually preferable at this point to heat the material containing the stabilizer at an elevated temperature in excess of 145° F. and desirably in excess of 170° F. or more.

Following the addition of the stabilizing material thereto, the dispersion or emulsion is broken, whereby the oil or fat globules are coagulated and such oil or fat is released from the dispersion or emulsion. The oil globules are coagulated and the dispersion is broken by any means such as by the application of heat thereto, by centrifuging, rapid agitation, or similar means.

Where the dispersion is broken and the oil or fat globules released by the use of heat, the previous elevated temperature treatment need not

40

45

50

65

have been applied. Where the dispersion is broken, however, by agitation, the heat is desirable for application prior to the breaking of the dispersion.

- 5 The emulsifying material which serves in the aqueous dispersion to reduce or prevent contact between the dispersed fat or oil and the antioxidant material distributed in the aqueous phase, may be left in the final fat or oil or it may be removed by suitable refining or processing from the final fat or oil which has been broken or segregated from the dispersion and in either case the fat or oil will have unusually high stability and resistance against the development of oxidative deterioration.

Surprisingly, the oil or fat that is obtained following the breaking of the dispersion or emulsion is substantially free of the water soluble antioxagens added to the aqueous continuous phase 20 of the dispersion or emulsion, but even though the oil or fat is free of the added antioxagenic material, such oil is nevertheless substantially stabilized against oxidative decomposition.

- Surprisingly also, where the antioxagen is added 25 to a pure fat or oil, its effectiveness is much less than where it is added to the aqueous continuous phase of an oil or fat in water dispersion or emulsion and the emulsion or dispersion then broken, preferably by a heat treatment, to release the 30 oil and fat globules.

Among the water soluble antioxagenic materials that may be utilized are particularly the crude cane and beet sugars and their residues or mother liquors obtained during the commercial 35 refining procedures, such residues including sorghum molasses, blackstrap molasses, etc.

The crude cane and beet sugar materials which may most desirably be utilized are those which are directly obtained by extraction from the cane 40 or beet, followed by evaporation to crystallized form without bleaching or char filtration and which contain in addition to a high proportion of carbohydrates a small amount of impurities removed with the sugar from the original cane or 45 beet, as the case may be.

Such water soluble carbohydrate materials are removed during the breaking of the emulsion or dispersion but will nevertheless serve to stabilize the fat or oil contained in the emulsion and when 50 removed therefrom by the breaking of that emulsion or dispersion.

Although it is particularly desirable to use the substantially crude and unrefined cane and beet sugars, particularly in the case of the butterfat 55 emulsion described in Example I given below, refined cane or beet sugar or dextrose or similar water soluble carbohydrate material may be employed and even though such water soluble carbohydrate materials in substantially refined state 60 possess no antioxidant action when added to a pure fat or oil, they nevertheless show some slight effectiveness in retarding oxidative deterioration when added to an oil or fat in aqueous dispersion or emulsion, subjected to an elevated temperature and then with the aqueous emulsion or 65 dispersion broken to release the fat globule.

Example I

A butterfat emulsion containing 35% butterfat 70 in the dispersed phase was treated by adding thereto 2.0% of refined sucrose in one case and 2.0% of crude unrefined crude cane sugar in another case. In each instance, the butterfat emulsion was then heated to 180° F. for 5 minutes 75 and the emulsion was then broken by substantial

agitation so that the butterfat globules coalesce and rose to the surface of the container that was used for the beating operation. The butterfat that were thus obtained were compared in keeping quality and it was observed that the butterfat obtained from the emulsion to which the crude unrefined cane sugar had been added showed the best keeping quality but at the same time the butterfat obtained from the emulsion to which had been added the refined cane sugar was somewhat better in keeping quality than the butterfat obtained from the emulsion to which no addition had been made. This was particularly surprising in view of the fact that when pure refined cane sugar is added to pure butterfat no improvement is observed, and even when crude cane sugar is added to pure butterfat, the improvement in keeping quality is not comparable to that obtained by adding the crude sugar to the emulsion and then breaking said emulsion as described.

In addition to the use of the substantially crude and unrefined cane and beet sugars and their mother liquors, the alcoholic extracts obtained therefrom may also be utilized, such alcoholic extracts being obtained by dissolving, for example, one part by weight of the crude unrefined cane sugar in five parts by weight of ethyl alcohol, agitating at a slightly elevated temperature such as at about 100° F. and filtering out the undissolved carbohydrate portion, evaporating the alcohol soluble portion preferably under reduced pressure to leave a substantially viscous and rather dark colored ethyl alcoholic extract of the crude cane sugar.

The application of heat is desirable before breaking the emulsion or dispersion or during the breaking of the emulsion or dispersion. Where heat is employed to break the emulsion or dispersion and where such heat is preferably as high as 150° F. and most preferably at 170° F. or higher, no additional heat need be given. The heat that would be employed during the breaking of the emulsion is sufficient to give satisfactory antioxagenic protection, but at some stage during the operation heat should be employed.

These substances may be added to the emulsion or dispersion in an amount ranging from 0.005% to 3% against the weight of the fat or oil contained in the emulsion or dispersion. Generally, it is preferable to use less than 0.5% by weight of the antioxagenic material against the fat or oil weight contained in the emulsion or dispersion and such proportion will under normal circumstances give the usual desirable improvement in keeping quality and stabilization of the oil or fat.

In any event, it is desirable for the emulsion to be subjected to an elevated temperature prior to the breaking of the emulsion in order for the desired stabilization to be effected. This stabilization occurs even where the fat globules are subjected to substantial water washing in order to make sure that these water soluble materials are substantially removed during the water washing process.

For example, following the coalescing of the butterfat globules, the butterfat may be washed with water using from 1 to 10 times the amount of water against the weight of the butterfat and the butterfat will nevertheless be substantially stabilized against oxidative deterioration.

Among other materials that can be utilized in a like manner are the glucamines including methyl glucamine, ethyl glucamine, etc. In ad-

dition, the reaction products of sugar and ammonia may be prepared by merely adding the sugar to ammonia, permitting the sugar to react therewith and then recrystallizing the reaction product thereof. Such materials obtained being substantially water soluble and capable of addition direct to an emulsion or dispersion, which is then broken and which will serve to stabilize the fat or oil which has been coalesced or broken from the emulsion or dispersion to a much greater degree than would be obtained where the glucamine or the reaction product of ammonia and sugar were to be added direct to the oil or fat following the breaking of such emulsion or dispersion.

As indicated above, the application of heat at the time of the breaking of the emulsion or dispersion or prior to the breaking of such emulsion or dispersion is desirable.

It has been found most satisfactory, either before or during or after the segregation operation to subject the mixture of the fat and oil and the aqueous materials to a short elevated heat treatment, say at a temperature of above 212° F. and preferably 250° F. for a period varying from 15 seconds to 2 or 3 minutes or more with the result that substantially greater stability is obtained in the final fat material.

In the wet or steam rendering of lard, oleo oil, mutton grease, Neat's foot oil, or other fats and including also the rendering of fish oil, fish liver oils, etc., such as of cod liver oil, herring oil, mackerel oil, menhaden oil, whale oil, etc., the fat is in substantially aqueous suspension at the time of the rendering operation, such fat occupying the dispersed phase and the water occupying the aqueous continuous phase with the fish phospholipin and proteins serving as the emulsifying colloids.

To the rendering kettle as in the rendering of any one of the above materials may be added a relatively small amount, such as less than 3% of the substantially crude sugars and after these materials have been added to the rendering kettle and the oil or fat emulsion or dispersion subjected to an elevated temperature preferably as high as 220° F. to 250° F., there will be obtained a very substantial increase in the stability of the oil or fat which is rendered by the breaking of the emulsion and the coalescing of the fat or oil globules.

Example II

In a similar manner, methyl glucamine was added to chopped hog fat which was then subjected to a steam rendering operation at 245° F. in which the fat of the hog or the lard became dispersed in the aqueous phase at the time of the steam rendering. Following the coalescing and release of the oil globules, the lard obtained was compared in stability with lard prepared from a similar lot of chopped hog fat and rendered similarly, such lard after rendering having added to it 0.1% of methyl glucamine. It was observed that the lard which had been rendered in the presence of the methyl glucamine and with the methyl glucamine occupying part of the aqueous continuous phase showed much superior keeping qualities as determined by subjecting the lard to test on the Swift Stability Apparatus than the lard which was rendered in the presence of the methyl glucamine and which after rendering was substantially free of the methyl glucamine.

In the rendering procedure, the higher the

temperature at the time the oil is dispersed in the aqueous continuous phase in the presence of the substantially water soluble antioxygenic material, the greater the stabilization or antioxygenic action exerted upon the oil.

For example, it seems desirable for the rendering to be conducted at temperature of about 220° F. to 250° F. or even higher and where the rendering is conducted at temperatures as high as 300° F. to 350° F. in the absence of these water soluble antioxygenic materials, even greater stabilization is obtained than where the lower temperatures are employed.

In addition to the use of the water soluble antioxygenic materials referred to, there may also desirably be employed for addition to the aqueous continuous phase of the oil in water emulsion or dispersion, combinations of materials along with sugars, such as combinations of sugars with (a) phosphatides, phospholipins, phosphoric acid, or acid phosphates and (b) the polyhydroxy polycarboxy aliphatic acids such as tartaric acid, citric acid, maleic acid, etc.

In the case of a product such as lecithin which is substantially oil soluble, that product may be utilized in accordance with this invention for addition to the water phase so that it does not find its way into the dispersed oil or fat phase of the emulsion or dispersion by incorporating it in a major proportion of sugar, and preferably a finely powdered sugar, such as powdered sucrose or powdered dextrose, although granulated sucrose may also be employed.

For example, when 50% soya lecithin is admixed thoroughly with 50% of powdered cane sugar, and preferably with 75% of powdered cane sugar, a satisfactory powdered product is obtained which will readily go into aqueous suspension or into the aqueous continuous phase of an oil in water emulsion or dispersion. Even though lecithin is normally soluble in oil, nevertheless when it is prepared in this manner mixed with water soluble carriers, such as sugar, powdered skim milk, etc., it will be substantially soluble in the aqueous continuous phase.

Where combinations of sugar and lecithin are employed, they are desirably first boiled in an aqueous solution before being added to the emulsion containing an oil in the dispersed discontinuous phase. For example, a mixture may be prepared comprising equal parts by weight of dextrose and lecithin and this mixture may be added to 5 parts by weight of water to every 1 part of the dextrose lecithin combination and then heated to boiling in order to obtain a thorough mixture of the dextrose lecithin combination in the water which will produce a rather milky or cloudy solution. This solution may then be added to the aqueous continuous phase of an oil in water emulsion and the dextrose lecithin combination will remain dispersed in the aqueous phase, nevertheless stabilizing the oil or fat discontinuous phase even after the emulsion has been broken and the oil or fat globules coalesced or released from the emulsion.

Example III

To a butterfat emulsion similar to the emulsion described in Example I was added 0.3% by weight of an intimate mixture comprising 70% powdered anhydrous dextrose and 30% soya lecithin in powdered form. After thorough admixture therein, the butterfat emulsion was heated to 175° F. for 10 minutes, cooled and then agitated to remove the butterfat. The butterfat

hus obtained was very materially improved in keeping quality over butterfat similarly prepared ut without treatment with the dextrose-lecithin combination at the elevated temperature.

In accordance with this invention, the anti-oxidants described may be added to the aqueous base of an oil, that is in the process of refining such as in the process of causticating where large quantities of moisture are present and where the antioxidant may be employed in the aqueous base in the course of such refining process to ve protection to the fat phase. Following the idition of the water soluble antioxidants to the ter phase in the course of the refining of such ls, such as of cottonseed oil, corn oil, soya bean l, etc., and following the breaking of the emulsion or dispersion, the oil is released free of the itioxidant but nevertheless stabilized against idative deterioration.

In accordance with this invention an oil or fat ay be placed into a dispersed or emulsified form, ated with the water soluble antioxygenic mate- l and the emulsion or dispersion broken. An-her method is to start with an oil or fat which rmally occurs in its emulsified or dispersed ase and to treat that emulsion with the water uble antioxygenic material. Then the emul- n or dispersion may be treated at an elevated perature to break the emulsion.

In addition to the treatment of the glyceride ; or fats, mineral oils may similarly be treated stabilize them, as in the preparation of emul- l containing the antioxygenic material in the eous continuous phase.

This invention may also be employed in the am distillation of the essential oils, such as aniol, oil of orange, oil of lemon, etc. When antioxygenic water soluble material such as de cane or beet sugar as described above is ed to the aqueous continuous phase of the erial from which these various oils are dis- d by steam distillation, and where the tem- ture of distillation is at least at 150° F. and erably at 175° F. or higher, the oils will be stantially stabilized against oxidative de- oration and materially improved in keeping ity.

The process of the present invention is partic- lly advantageous in that it eliminates from final oil or fat any objections of impurities or amination as might result from the anti- oxiants. While many antioxidants are objec- ble from the viewpoint of labeling, edibility, when the oil or fat is prepared in a con- n substantially free of the antioxidants, ap- lty a much higher grade of oil or fat is ob- d which need not be labeled or contaminated. Though this invention relates particularly to stabilization of glyceride oils that are re- d from the dispersed phase of an emulsion, theless it has also been observed that where water soluble or water miscible antioxygens as the crude sugars or similar antioxygenic ict described are added to the aqueous con- us phase of the emulsion containing the oil t globules in the dispersed discontinuous and particularly where such emulsions are subjected to an elevated temperature such in excess of 170° F. and desirably in excess of F., even where the emulsion is not sub- lty broken and the oil is retained in the itinuous phase of the emulsion with the xygens present in the aqueous continuus

phase, the said dispersed oil or fat globules will be substantially stabilized against oxidative de- terioration, although, in accordance with this invention, the oil or fat globules may desirably be coalesced and removed from the emulsified form.

In the drawing are shown diagrammatically four different specimens of materials for the pur- pose of illustrating the stabilization method of the present invention. Each of the Figs. 1 to 4 shows a vessel in diagrammatic transverse sec- 10 tion which contains a solid, plastic or liquid material. In Fig. 1 in the vessel 10 is shown a 100% pure glyceride oil or fat which may be in refined condition which contains particels of an antioxidant. When antioxidants are added di- rect to a 100% pure oil or fat, the stabilization is not as thoroughly obtained as by the process of the present invention and it is usually nec- essary or desirable to remove the antioxidant from the oil or fat so as to eliminate the presence of 20 foreign materials, to avoid contamination or de- creased edibility, loss in flavor, or the development of micro-organisms. Even if the oil containing the antioxidant particles is dispersed in water as shown in Fig. 2 with the dispersed oil globules 13 being encircled or encased by an emulsifying film 14, the fat or oil is not as effectively pro- tected as by the present invention even though most intimate contact with the antioxidant is 25 obtained. With certain kinds of antioxidants 30 particularly, the presence of water will greatly reduce their activity and effectiveness.

In Fig. 3 the antioxidant particles are distrib- uted in the water phase 15 and not in the oil 35 globules 13 and they are separated from the oil globules 13 by the emulsifying film 14 which pre- vents contact or mixture between the water and the oil. In Fig. 4 is shown the stabilized oil or fat which may be obtained by breaking the emulsion or dispersion of Fig. 3, segregating the fat or oil globules, and removing substantially all of the antioxidant 12 with the water or aqueous phase, 40 in spite of which a highly stabilized oil or fat is obtained.

By the expression "animal glyceride oil" is in- cluded both the glyceride oil obtained from meat 45 as well as the glyceride oil obtained from fish.

This application is a continuation in part of copending applications, Serial No. 260,898 filed March 10, 1939, and Serial No. 292,613 filed 50 August 30, 1939, and through said applications continues the subject matter of application, Serial No. 135,169 filed April 5, 1937.

Having described my invention, what I claim is:

1. A process of stabilizing glyceride oils and fats subject to oxidative deterioration against such deterioration which comprises adding a small amount of a mixture of an added sugar and an added phosphatide as an antioxidant to the aqueous continuous phase of a dispersion con- taining the oil and fat in the dispersed phase thereof, and subjecting the dispersion to an elevated temperature of over 220° F., and then breaking the dispersion to obtain a stabilized oil, substantially devoid of the antioxidant contained in the original aqueous continuous phase.

2. A process of producing a stabilized lard which comprises mixing together hog fat and water containing a small amount of a sugar as 70 an antioxidant, subjecting the mixture with agi- tation to a temperature in excess of 220° F., and then removing the lard from the water containing the antioxidant, whereby a lard is produced which is substantially free of the antioxidant 75

and which is stabilized against oxidative deterioration.

3. A process of producing a stabilized animal glyceride oil which comprises mixing together animal fat and water containing a sugar as an antioxidant, subjecting the mixture with agitation to a temperature in excess of 220° F., and then removing the oil from the water containing the antioxidant, whereby an oil is produced which is substantially free of the antioxidant and which is stabilized against oxidative deterioration.

4. A process of stabilizing a glyceride oil subject to oxidative deterioration against such deterioration which comprises adding a small amount of a sugar as an antioxidant to the aqueous continuous phase of a glyceride oil dispersion containing the glyceride oil in the disperse phase thereof, subjecting the dispersion to an elevated temperature of over 145° F., and then removing the glyceride oil which is in a stabilized condition and which is substantially devoid of the antioxidant contained in the original aqueous continuous phase.

5. A process of stabilizing a glyceride oil sub-

ject to oxidative deterioration against such deterioration which comprises adding a small amount of a sugar as an antioxidant to the aqueous continuous phase of a food emulsion containing the glyceride oil in the disperse phase thereof, subjecting the emulsion to an elevated temperature of over 145° F., and then breaking the emulsion to obtain a stabilized glyceride oil, substantially devoid of the antioxidant contained in the original aqueous continuous phase.

6. A process of stabilizing a glyceride oil subject to oxidative deterioration against such deterioration which comprises adding a small amount of a sugar and also a phosphatide as an antioxidant to the aqueous continuous phase of a glyceride oil dispersion containing the glyceride oil in the disperse phase thereof, subjecting the dispersion to an elevated temperature of over 145° F., and then removing the glyceride oil which is in a stabilized condition and which is substantially devoid of the antioxidant contained in the original aqueous continuous phase.

SIDNEY MUSHER.
